UNITED STATES PATENT OFFICE.

WILLIAM H. GOLDSMITH, JR., OF BIDDEFORD, MAINE, ASSIGNOR TO SACO-LOWELL SHOPS, OF BOSTON, MASSACHUSETTS, A CORPORATION OF MASSACHUSETTS.

SPINNING AND TWISTING MACHINE.

1,263,055.

Specification of Letters Patent. Patented Apr. 16, 1918.

Application filed October 25, 1915. Serial No. 57,668.

To all whom it may concern:

Be it known that I, WILLIAM H. GOLDSMITH, JR., of Biddeford, in the county of York and State of Maine, a citizen of the United States, have invented a new and useful Improvement in Spinning and Twisting Machines, of which the following is a full, clear, and exact description, reference being had to the accompanying drawings, forming 10 a part of this specification in explaining its nature.

The object of the present invention is to simplify and otherwise improve the general structure of the machine and essentially to 15 provide means whereby the relation between the ring rails and the driving parts may remain constant whatever the adjusted position of the rails may be.

The invention can best be seen and understood by reference to the drawings in which only such parts of a spinning machine are shown as are necessary to a proper understanding of the invention, and in which—

Figure 1 is a plan of the machine.

Fig. 2 is a side elevation.

Fig. 3 is an end elevation.

Fig. 4 is a section on the line 4—4 of Fig. 2, and

Fig. 5 is a section on the line 5—5 of 30 Fig. 2.

Referring to the drawings:—

The supporting base structure of the machine consists of a series of supporting frame pieces or standards 1 which are arranged intermediate the ends of the spindle rail 2 and are connected by the spindle rails. These rails are fixed to the frame pieces in a manner to permit of their vertical adjustment. Such attachment is obtained by bolts 4 which pass through vertical slots 5 in the frame piece and are secured by nuts 6. The adjustable support of the spindle rails is further obtained by bolts 7 which extend vertically through lugs 8 on the frame pieces 45 and bear against the under sides of the spindle rails.

The spindle rails are also adjustably secured to, and assist in the support of an end frame 10 which carries various customary 50 geared mechanisms (not shown) which assist in the operation of the machine in the usual manner. The attachment between the spindle rails and end frame is attained by means of bolts 11 which pass through vertical slots

12 formed in the end frame and through the flanged ends 13 of the spindle rails, and are secured by nuts 14.

15 is the driving drum or cylinder from which the spindles (not shown) mounted upon the spindle rails, are driven in the usual manner. 16 is the main drive shaft on which the cylinder 15 is mounted and by which it is rotated, this shaft, in fact, driving all of the remaining operative parts of the machine (not shown). The shaft 16 is 65 operated by pulleys arranged upon it and of which the pulley 17 is a fixed pulley and 18 an idler pulley.

In accordance with the purpose of my invention arrangement is made whereby the main drive shaft 15, together with the cylinder and pulleys thereon, may be moved simultaneously with the spindle rails. In other words, the arrangement is such that the drive shaft and pulleys driving the same together with the driving cylinder may occupy a constant relative position with relation to the spindle rails whatever the adjusted position of these rails may be.

Attached to those ends of the spindle rails opposite the frame 10 is an outrigger frame 20. This frame consists of a cross-bar 21 and a rounded bar or rail 22 the ends of which connect with the ends of the cross-bar 23. The entire outrigger structure is secured to the ends of the spindle rails by bolts 24 to project in extension thereof and lie in substantially the same plane with the plane of the two spindle rails. The outrigger structure provides a support 80 for one end of the drive shaft 16, there being formed upon the cross-bar 21 and rail 22 of the outrigger structure bearings 25 in which the shaft turns. The outrigger structure provides, also, a housing within which 90 the fast and loose pulleys are contained, the same being arranged upon the main shaft between the bearings 25.

The main drive shaft is centrally supported by a cross-bar 26 which is secured to the spindle rails at approximately the center of the machine and is provided with a bearing 27 through which the drive shaft extends, substantially as shown in Fig. 5.

That portion of the drive shaft adjacent 105 the frame 10 at the outer end of the machine from the outrigger frame, is supported by a cross-bar 28 which is secured to the ends of

the spindle rails and is provided with a central bearing 29 through which the drive shaft extends.

From the above description it will be seen 5 that the main drive shaft, the pulleys driving this shaft and the main driving cylinder are all movable with the spindle rails and accordingly maintain the same relative positions at all times with respect to these rails, whatever the adjusted position thereof 10 may be.

Having thus fully described my invention, I claim and desire to secure by Letters Patent of the United States:—

15 In a spinning or twisting machine, the combination comprising spindle rails, a frame supporting said rails and interposed

between the ends thereof, a cylinder, a cylinder shaft, a driving pulley affixed to said shaft, means for securing said spindle rails to said frame to have vertical adjustment thereon, an auxiliary outrigger frame fixed to said spindle rails at one end of the machine in extension of said rails and occupying a constant relative position with relation thereto, said outrigger frame providing a bearing for said shaft and a housing or guard for said pulley, and other means for assisting in the support of said shaft at the other end of the machine whereby it and the cylinder carried thereby may occupy a constant relative position with relation to said spindle rails.

WILLIAM H. GOLDSMITH, JR.
